CONCEALED-NAIL JOINT FOR SHEET-METAL ROOFING.

1,179,085.

Specification of Letters Patent.

Patented Apr. 11, 1916.

Application filed July 26, 1915. Serial No. 41,977.

To all whom it may concern:

Be it known that I, CHRISTOPHER B. EDWARDS, a citizen of the United States of America, and a resident of Covington, in the county of Kenton and State of Kentucky, have invented a certain new and useful Improvement in Concealed-Nail Joints for Sheet-Metal Roofing, of which the following is a specification.

- 10 This invention relates to sheet-metal roofing, or, more particularly speaking, to a concealed-nail joint for that class of roofing, and the special object of the invention herein is to enable the roof-layer to drive the 15 nails direct into the apex or crown of a lapped crimp-joint and to cap each head of the nail with a short and narrow transversely-arranged independent strip of metal that is adapted to be readily bent and folded 20 over said head of the nail to conceal it from view and at the same time reduce leakage at that point to a minimum, assuming that any leakage could result owing to the hole produced in driving the nail.
- 25 A very important object of the invention, as well, is the material saving of considerable metal that has heretofore been necessary in the laying of a crimp-joint in which an extra allowance of material has been 30 made in providing a foot-hold for the nail within or beneath the joint and in direct contact with the sheathing, the short and narrow independent transverse strips of metal required in producing my individual- 35 nail concealing-caps being well adapted to be made from small pieces of metal or practically valueless scrap and thus, also, reducing the waste and cost of material to a decided minimum.
- 40 The details of structure in connection with various analogous forms of my invention herein will be fully hereinafter described in connection with the accompanying sheet of drawings, in which latter,

- 45 Figure 1 is a transverse section of a crimp-joint of sheet-metal roofing, embodying my invention herein showing one form of my capping and concealing strip in normal, horizontally-extended position ready for 50 bending or folding over on the head of the nail, which latter has been driven into fastening-place through the apex of the joint into the supporting-sheathing below; Fig. 2, a view similar to Fig. 1, but showing my

said capping and concealing strip bent and 55 folded over the head of the nail into covering and concealing position; Fig. 3, a view similar to the preceding two views, but showing a slight variation in the placing of the usual lead-washer, the latter, in this 60 view, being in contact with the upper surface of the capping-strip, while in the preceding two views said lead-washer is in contact with the lower face of said capping-strip; Fig. 4, a transverse section similar to 65 the preceding three views, but showing my capping-strip in its preferred form unaccompanied by a lead-washer or any other washer, but intended as being made of a thick strip of lead itself so as to discard the 70 use of a washer; Fig. 5, a transverse section similar to the preceding views, but with my capping-strip provided with a fold or hook-formation along its lower edge that is adapted to engage beneath the lower edge of the 75 lapping-member of the crimp-joint and with its free end extended upwardly ready for bending or folding down upon the fastening-nail head, the nail not being driven through the capping-strip in this instance 80 but provided with a lead-washer between its head and the apex of the joint; Fig. 6, a view similar to Fig. 5 and of its same structure, but with the capping-strip bent and 85 folded down in concealing and protecting position on the driven nail head; Fig. 7, a transverse section, similar to Figs. 5 and 6, with the nail driven direct into the apex or 90 crown of the joint and with a similar capping-strip, but with the lower inwardly-turned hook end thereof engaging a slit or narrow slot made in the outer lapping-member of the crimp-joint and showing the upper or free end of the capping-strip bent 95 over and folded down upon the head of the nail in the same manner as shown in Fig. 6; Fig. 8, a view similar to Fig. 7, but with my capping-strip having its lower end bent so as to enter the slit or narrow slot in the outer-member of the lapping crimp-joint 100 and then bent into outwardly-disposed hook-form so as to engage the lower edge of said outer-member of the crimp-joint on the outer face thereof; Fig. 9, a fragmentary plan view of Fig. 1; Fig. 10, a fragmentary 105 plan view of Fig. 3; Fig. 11, a fragmentary plan view of Fig. 4, which is practically the same as Fig. 9, but with an oval-shaped

capping-strip; Fig. 12, a fragmentary plan of Fig. 6; Fig. 13, a fragmentary plan of Fig. 7; and Fig. 14, a fragmentary plan of Fig. 8.

5 In Figs. 1 to 8, both inclusive, 1 indicates the ordinary sheathing; 2, the fastening-nail; 3, the lead-washer; 4, the body-portion of one of the roofing-sheets having the lower or lapped member of the crimp-joint; 5 the 10 next adjacent roofing-sheet that has the usual inverted-V-shape outer or lapping member of the joint; and 6 the nail-head. In these views, I have shown for example and convenience, a lapped crimp-joint, 15 whose lower or lapped member is composed of a slanting part 7, a guttered or channeled apex or crown 8, a slightly slanting part or leg 9, a gutter or base 10, and an upwardly-turned, slanting flange 11, and whose upper 20 or lapping member is composed of an inclined or slanting part 12, a horizontal apex or crown 13 and an inclined or slanting outer-limb 14, that are adapted to fit snugly in place upon said lower or lapped member. 25 Of course, it is not essential to make the crimp-joint just as I show it, but it is desired that it have an elevated apex or crown, with sloping sides and an internal stiffening or supporting, approximately perpendicular member to provide for the driving 30 of the nail through the said apex or crown, whereby both lapped-members of the joint are pierced by the nail mid-width of the joint.

35 In Figs. 1 and 2 I have shown one form of my nail protecting and concealing device, and in which the lead-washer 3 lies between the inner or fastening end of the narrow, or short, transverse concealing-strip 40 15 and in contact with the apex 13 of the lapping-member of the joint, the head 6 of the nail lying in contact with the outer face of the said fastening-end of the concealing-strip. The said lead-washer is thus 45 concealed beneath the strip 15 when the latter has been bent over the nail-head 6 along the line 16 and thence over the opposite edge of the nail-head along the lead-washer and with its outer end lying in contact 50 with the member 14 of the lapping-member of the joint, as best shown in Fig. 2. In Fig. 3, I show how the said lead-washer is arranged on the nail-shank directly beneath the head of the nail and on top of 55 the said fastening-end of the concealing-strip 15, the outer, horizontally-disposed, free-end of said strip 15 being adapted to be readily bent and turned over the washer and nail-head, the same as in Fig. 2, but 60 with the said fastening-end of the strip beneath said washer.

In Fig. 4 I show my preferred form of device in which a thickened strip of metal 15 is used to serve as a concealing one, its inner or fastening end being in contact with

the lower face of the nail-head 6 and omitting the lead-washer, the strip 15 itself, in this view, being a short and narrow one and of lead and adapted to be readily bent over the head of the nail, the same as in said Fig. 2.

In Fig. 6 I have shown the concealing-strip 15 as being made with a lower inwardly-turned hook-end 17 that is adapted to engage beneath the lower edge of the outer-member 14 of the lapping-member of the joint, and the upper end of the strip is passed onward over the nail head, to lie flatly in contact therewith and thence is turned in a slanting manner downwardly until its free end rests in contact with the outer face of the slanting member 12 of said lapping-member of the joint. In Fig. 5, however, I show how the free-end of the strip 15 extends upwardly and in position ready for bending or turning down upon the nail head, as seen in Fig. 6.

In Fig. 7 I have shown the concealing-strip 15 of the same form as that seen in Figs. 5 and 6, but the lower hook-end 17 is shown in engagement with a slit or narrow slot 18 made parallel and close to the lower edge of the outer lapping-member 14 of the joint; and in Fig. 8 I have shown the said concealing-strip as being made with a hook-formation 19 that is disposed outwardly and has an elbow 20 therein, such elbow passing inwardly through the slit or narrow slot 18 made in the outer lapping-member 14 and with said outwardly-turned hook-formation 19 engaged under the lower edge of said lapping-member 14 for securing the said concealing-strip in place on the joint coincident with a fastening-nail 2. In each of Figs. 5, 6, 7 and 8, the lead-washer 3 is shown between the nail head and the apex of the joint, and the upper or outer free-end of the strip 15 in each of the views 7 and 8 is lapped or folded over the nail head in the same manner as seen in Fig. 6.

It will be seen that there is but a slight variation in connection with each of the means of fastening one end of the concealing-strip to the joint, whether direct to the joint itself or to the fastening-nail and all these forms are believed to be comprehended under the preferred form shown in Fig. 4 and being under claim 1 that shortly follows herein.

In the plan views, 9 to 14, both inclusive, the concealing-strips are each made of a rectangular form and somewhat elongated, excepting that the concealing-strip 15 seen in Fig. 11 is of oval form that might be considered as giving a little more attractive appearance to the roof when finished than the rectangular form of the other views. The plan views, Figs. 9 to 11, both inclusive, show the concealing-strip as it appears in normal position ready for bending or fold-

ing into concealing position over the nail head in each view, and the plan views, Figs. 12 to 14, both inclusive, show the concealing-strips in their final seating or concealing position upon the nail head in each view.

Although the nails used in connection with sheet-metal roofing are roughened or barbed at their lower pointed ends and thereby intended to hold firmly from accidental withdrawal from the sheathing, it is reasonable to assume and state herein that the capping or concealing strips shown are each adapted to aid in preventing the displacement or loosening of the nails:

15 The metal used in the short, narrow transverse concealing-strips can ordinarily be taken from small pieces of scrap material, although it is obvious it can be made from any strips of sheet-metal of suitable width 20 and cut down to the desired narrow lengths so as to properly lap or fold over the nail heads and perform the desired result herein.

It is obvious that the concealing-strip need not be much, if any, wider than the diameter of the lead-washer used in connection with each nail-head, thereby reducing capillary attraction of any falling water to a minimum, whereas a broader strip would have a greater tendency to capillary-attraction 25 and to a consequent lodging of the water around the respective nails and washer to seep through the respective nail holes and thence beneath the lapped joint.

I claim:—

1. In a lapped, inverted-V-shape crimp-joint for sheet-metal roofing having a series of spaced fastening-nails driven through the apex or crown thereof into the sheathing beneath, a similar series of elongated, narrow, transverse, independently-arranged 40 flat plates or strips of flexible sheet-metal each of which is adapted to be fastened at one end of the crimp-joint but with its remaining length free to be bent over and laid down upon the said fastening-means for concealing the latter and providing a leakage-cover for it, either with or without a washer. 45

2. In a lapped, upright crimp-joint for sheet-metal roofing having a series of fastening-nails driven through the apex or crown thereof into the sheathing beneath, a similar series of narrow, elongated, transverse, independently-spaced flat strips of flexible sheet-metal each of which is adapted 50 to be connected at one end to the apex of the crimp-joint by means of one of said fastening-nails but free the remainder of its length to be bent over and laid down upon the nail-head for concealing the latter and covering it to avoid leakage around the nail 55 where it enters the joint. 60

CHRISTOPHER B. EDWARDS.
